UNITED STATES PATENT OFFICE.

CÆSAR NEUMANN, OF NEW YORK, N. Y.

IMPROVEMENT IN HOOP-SKIRTS.

Specification forming part of Letters Patent No. 56,787, dated July 31, 1866.

To all whom it may concern:

Be it known that I, CÆSAR NEUMANN, of the city, county, and State of New York, have invented a new and useful Improvement in Hoop-Skirts; and I do hereby declare that the following is a full, clear, and exact description thereof, which will enable others skilled in the art to make and use the same, reference being had to the accompanying drawings, forming a part of this specification, in which—

Figure 1 represents a side elevation of this invention. Fig. 2 is a partial side view of one of the tapes detached in a larger scale than the previous figure. Fig. 3 is a longitudinal vertical section of the same.

Similar letters of reference indicate like parts.

This invention consists, first, in arranging the pockets or shirrs which support the hoops in sections of two or more shirrs, each in such a manner that a hoop-skirt is obtained in which two or more wires are close together and which presents a novel and unique appearance.

It consists, also, in arranging the wires of a hoop-skirt in sections of two or more each, said wires being single or double, in such a manner that a strong, durable, and light skirt can be produced.

A represents a hoop-skirt, the wires B of which are supported by the tapes C. These tapes are provided with shirrs or pockets a, which are woven in sections, each section comprising two or more pockets, as clearly shown in Figs. 2 and 3 of the drawings. The wires of the hoop-skirt are thereby divided in

sections of two or more wires each, according to the number of shirrs in each section of pockets, and a skirt can be produced which excels in strength and lightness, and which can be made cheap.

It must be remarked that the wires may be supported or fastened to the tapes by any suitable means, and I do not wish to confine myself to the precise arrangement shown in the drawings. The number of wires in each section will generally be three in the upper and four in the lower sections, as shown in Fig. 1, though I do not wish to confine myself to any particular number, and reserve the right to change the same as may be desirable.

By arranging the wires close together in sections they are not liable to break. Thinner wire can be used than in ordinary skirts, and the cost of the skirt is materially reduced, and at the same time an article is produced which presents a unique and novel appearance, and which will be sought after by the public.

I do not claim placing a series of metallic strips edge to edge in a common covering.

What I claim as new, and desire to secure by Letters Patent, is—

A hoop-skirt having its wires arranged in sections or clusters, each section comprising two or more wires placed near together in separate pockets, substantially as described, as a new article of manufacture.

CÆSAR NEUMANN.
